CONTAINER CLOSURE

Herman Pesch, Fulton, and Isaac L. Wilcox, South Fulton, N.Y., assignors to Sealright-Oswego Falls Corporation, Fulton, N.Y., a corporation of New York

Application July 6, 1959, Serial No. 825,348

3 Claims. (Cl. 215—41)

This invention relates to container closures and particularly to closures moulded from sheet plastic material for application to bottle tops having an external bead, such as milk bottles. The closure to which this invention is directed is of the general type disclosed in Patent No. 2,869,746, to I. L. Wilcox, January 20, 1959. Closures of that type are used extensively as caps for what is known as the 38 millimeter milk bottle.

This invention has as an object a closure which, by its structural arrangement, can be moulded from plastic sheeting of considerably lighter caliber than heretofore used. Inasmuch as about eighty percent of the total cost of the closure resides in the cost of the plastic sheet, a substantial reduction in the caliber of the sheeting effects a substantial reduction in the cost of the closure.

The invention has as a further object a bottle closure moulded from exceedingly light caliber sheet plastic material embodying an arrangement whereby the cap is quickly and properly applied to the bottle top by conventional capping heads, without any deleterious deformation of the cap and which, when applied, is effective to seal the bottle and which will not become displaced in the usual handling of the bottle.

The invention consists in the novel features and in the combinations and constructions hereinafter set forth and claimed.

In describing this invention, reference is had to the accompanying drawings in which like characters designate corresponding parts in all the views.

In the drawings:

Figure 1 is a side elevational view of a closure embodying our invention.

Figure 2 is a transverse sectional view of two of the caps illustrating the caps in stack formation.

Figure 3 is a side elevational view of the closure applied to a bottle top, the left portion of the figure being in section.

The closure consists of a top discoidal portion 10 which extends over the top of the bottle B. A skirt portion 11 depends from the periphery of the portion 10 and terminates in an outwardly extending radial flange 12. This flange extends outwardly and upwardly, as seen best in Figure 2 of the drawings. A cylindrical flange 13 depends from the peripheral edge of the flange 12 and terminates in an outwardly flared rim 14.

The cylindrical portion 13 is substantially the same diameter, or slightly greater than the maximum diameter of the bottle bead as at 16 whereby, upon initial relative axial movement between the bottle and the closure, the closure becomes centered on the bottle. The diameter at the lower edge of the skirt, adjacent the flange 12, is slightly less than the diameter of the bottle bead at the point 20 engaged by the lower edge of the skirt when the cap is applied to the bottle.

The skirt 11 is of conical formation. However, the angle of inclination of the skirt in regard to the axis of the closure is relatively slight whereby the mid point of the skirt, indicated at 21, Figure 2, is of such diameter

2

as to cause the skirt 11 to conform to and snugly engage the bead of the bottle when the cap is applied thereto, but yet not to cause the skirt portion to be stretched beyond its elastic limit. For application to the standard 38 millimeter milk bottle, the angle of the skirt 11 is 4° to 4½°, as distinguished from the conventional plastic cap having an angle of 8°, or more.

The flange 12 is inclined outwardly and upwardly to provide a seat on which the rim 14 of the cap next above 10 is positioned when the caps are arranged in stack formation. This inclination of the flange 12 results in the skirts 11 of the caps in the stack being spaced slightly apart, or not snugly engaging each other. Due to the slight taper of the skirts of the closures, any engagement 15 of the skirts in the stack formation would make it difficult to separate the caps in the stack. Accordingly, because of the inclined flange 12, the caps are conveniently separated in the stack for feeding and application to the bottle tops but yet the skirts 11, in an axial 20 direction, are of maximum length for maximum engagement with the bottle head.

These caps are supplied to the bottle tops by an annular applicator member positioned on the rim 14. When 25 relative axial movement is effected between the applicator and the bottle, considerable pressure is applied on the rim 14 to effect application of the cap to the bottle. The rim 14 is formed with one or more circumferentially 30 extending corrugations or ridges 24. This corrugation serves to stiffen the rim and to prevent it from pleating due to the downward force applied by the cap applicator. In order for the rim 14 to fold downwardly and therefore become of reduced diameter, the rim must pleat in 35 one or more places. Due to the fact that this cap is formed of exceedingly thin plastic sheeting in the order of .006 to .008 of an inch in thickness, there would be a tendency of the rim to pleat and fold down, which would prevent proper application of the cap to the bottle top. However, the corrugations 24 effectively serve to 40 prevent this pleating even though the cap is formed of such thin material.

What we claim is:

1. A container closure molded of thin sheet plastic material for application to containers having an external bead at the top edge thereof, said closure comprising a central discoidal top portion for overlying the top of the container and being of less diameter than the container bead, a skirt depending from the periphery of said discoidal portion, said skirt terminating at its lower edge in an external radial flange inclined upwardly and outwardly, a cylindrical portion depending from the periphery of said flange and having a diameter comparable to the diameter of the container bead, said cylindrical portion terminating in an outwardly flared rim and said rim being formed with a circumferentially extending reinforcing ridge.

2. A container closure molded from thin sheet plastic material for application to containers having an external bead at the top edge thereof, said closure comprising a central discoidal top portion for overlying the top edge of the container and having a diameter less than the container bead, a skirt diverging downwardly from the periphery of said discoidal portion at an angle not to exceed 4½°, said skirt terminating at its lower edge in an external radial flange, a cylindrical portion depending from the periphery of said flange and having a diameter comparable to the diameter of the container bead, said cylindrical portion terminating in an outwardly flared rim and said rim being formed with a circumferentially extending reinforcing ridge.

3. A container closure molded of thin sheet plastic material for application to containers having an external bead at the top edge thereof, said closure comprising a

3

discoidal portion for overlying the top of the container and having a diameter less than the container bead, a conical skirt depending from the periphery of said discoidal portion at an angle not greater than $4\frac{1}{2}^{\circ}$ and terminating at its lower edge in an external radial flange inclined upwardly and outwardly, a cylindrical portion

4

depending from the periphery of said flange and having a diameter comparable to the diameter of the container bead, said cylindrical portion terminating in an outwardly flared rim formed with a circumferentially extending reinforcing ridge.
